UNITED STATES PATENT OFFICE.

HARRY WINBERG AND CHARLES WINBERG, OF WALTHAM, MASSACHUSETTS.

EXTENSIBLE TABLE.

1,363,631.

Specification of Letters Patent. Patented Dec. 28, 1920.

Application filed March 24, 1919. Serial No. 284,542.

To all whom it may concern:

Be it known that we, HARRY WINBERG and CHARLES WINBERG, citizens of Sweden, residing at Waltham, in the county of Middlesex and State of Massachusetts, have invented certain new and useful Improvements in Extensible Tables, of which the following is a specification.

This invention relates to improvements in extensible tables. More particularly it relates to dining room tables and the like in which as hitherto constructed it is customary for the table top to be made in two halves that can be pulled apart for filling pieces or boards to be inserted between them. Such boards ordinarily are unsightly, have to be stored in some other part of the house, are heavy and clumsy for women to transport, and are otherwise objectionable. In houses where it is necessary to reduce the table after each meal, the work involved in handling the filling boards amounts in total to an appreciable burden. It is an object of the present invention to provide for storing the filling pieces within the top of the table itself; to arrange so that they are quickly and conveniently put into use, with the table extended more or less as desired, and are with equal ease returned to their places of storage. It is another object to accomplish this by means which are convenient and unobtrusive, the mechanical appliances incidentally involved being concealed from view, and in a measure automatic. Specifically, it is one feature to accomplish this by the use of flexible filling boards, and to provide supports and mechanism for guiding and holding them while set, while retired, and in transition. It is another feature to provide movable rails which automatically retire to positions of concealment below the top when the table is closed and which rise to the level of the table top to co-operate with and constitute guides for the flexible filling parts as and when the table top is extended. Further features of the invention are to provide the other advantages that characterize the structure set forth herein as an illustrative embodiment of the invention; but it will be understood that the features of the invention may be applied in various ways. It is intended that the patent shall cover, by suitable expression in the appended claims, whatever features

of patentable novelty exist in the invention disclosed.

The accompanying drawings represent a table having three possible stages of extension.

Figure 1 is a plan of the table, in its extreme stage of extension;

Fig. 2 is a side elevation of the same;

Fig. 3 is a side elevation of the table, contracted;

Fig. 4 is a side elevation of the same on a larger scale, the outside rim being in section on the medial plane;

Fig. 5 is the same, but with the table top in the first complete stage of extension;

Fig. 6 is the same, but with the top extended to the third and final complete stage;

Fig. 7 is an end elevation, in section on the line 7-7 of Fig. 4.

Fig. 8 is an end elevation, in section on the line 8-8 of Fig. 5, as when the top is extended to either stage;

Fig. 9 is a detail seen in end elevation on a larger scale, showing a stop and the releasings therefor which act at the time of the completion of the first stage and in preparation for proceeding to the second stage;

Fig. 10 is an end elevation of a detail affecting the parts shown in Fig. 9, in section on the line 10-10 of Fig. 9;

Fig. 11 is a plan with the top removed, as in section on the line 11-11 of Fig. 2, showing the table fully extended, but with the filling sections in their position of retirement;

Fig. 12 is a bottom plan view of a detail, the interlocking support between the two halves of a filler.

The drawings represent the upper part of a table, which may have any suitable sort of base from which a pedestal 10 rises, carrying a rigid frame for the top comprising longitudinal bars 11, cross bars 12, 12^a, 12', and 12'', and an ornamental circular depending rim 13, the relations of which parts are best seen in Figs. 2, 3 and 11. The top proper has two halves 14 and 14', movable between the closed contracted or reduced position shown in Fig. 3, and the extended position shown in Figs. 2 and 1. In the latter, the filling pieces 15, 15', 16, 16', 17, 17' are seen in use as a part of the table top as are also the depressible rails or guides 22 and 22'. The general principle of the invention

is that each filling board is in halves capable of being moved in guides crosswise of the table. These are flexible, being capable of bending on the lines seen in Fig. 1; and are 5 shiftable from the position seen in Figs. 1 and 8 to that of Fig. 7. In the course of shifting each half of a filling board moves toward the other side, dips downward, and turns back underneath where it stays 10 concealed within the depending circular rim and frame.

The construction by which this is brought about is as follows:

One-half of the table top rests upon a 15 pair of slides 21, fitted on the outer sides of the longitudinal members 11 of the frame, and the other half rests upon a similar pair of slides marked 21' and fitting on the inner sides of the same slide-carrying members 11 of the frame, as most clearly seen in Fig. 11.

The sections of table top may be secured to these sliding pieces in any suitable way, their fastening thereto being indicated in Fig. 11 by screw holes 20 in the parts 21 25 and 21'.

The middle abutting edges of the two halves 14, 14', of the table top have grooves 30, 30', one in the lower part of the upper half of the edge surface of each, as seen in 30 Figs. 4 and 10, and a recessed portion 31, 31' in the lower half of each of those edge surfaces. Adapted to be received within the recesses 31, 31', are two rails or guiding strips 22, 22', which rails extend crosswise of the 35 table and have in the lower halves of both of their edge surfaces grooves 32, 32', 33, 33' like the other grooves. The grooves are conveniently constituted by making a rectangular recess in the lower half of the edge and 40 by adding metallic plates 30^a, set into the under-side of the table top, and fastened on the under-side of the rails, so as to make the third side of the groove. These plates, which extend entirely across the table except 45 for a break in the middle as seen in Fig. 7, are conveniently held in place by screws, as seen in Fig. 10. The grooves thus made serve to guide the edges of the flexible fillers when the parts having them are properly positioned. The shifting of the rails from the 50 position illustrated in Fig. 3 to that of Figs. 2 and 1, is accomplished automatically by the pulling of the table top halves 14, 14' apart, and by the setting of the fillers. The 55 way of accomplishing it is perhaps best seen by considering Figs. 4, 5 and 6. Each of the rails 22, 22' carries a block, like that shown at 23, which may be secured to it by deeply sunken screws, one of which is seen in Fig. 9, 60 which block in side elevation has the peculiar form seen in Fig. 4, with a bottom edge inclined upward in the direction in which the block moves to extend the table, and with its lower part projecting in the same direction as shown in full lines in Fig. 4, forming 65

a lug 23^a which is adapted to strike the fixed cam block 24, and to be elevated by it, until the lug 23^a engages under the hook or lug 24^a of the block 24. The latter is fixed on one of the rigid members 12^a of the frame, 70 as seen in Fig. 9, where one of its fastening screws 24^b is represented. The members 12^a and 12^{a'} of the frame are so fixed in position, and the various blocks are so located with respect to them and to the rails and to each other, that when the block 23 is moved to the left, in Fig. 4, the high and leading end of the lower edge of block 23 strikes on the cam surface of block 24 and is raised to the level shown in Fig. 5, with its lug 23^a hooked 80 under the lug 24^a, thus carrying the rail 22 from the depressed position illustrated in Fig. 4 to the raised and ready for use position illustrated in Fig. 5, and stopping it there. Such a movement is brought to pass 85 by the action of the pin 25 whose position is seen in Fig. 4 a little to the right of the rear edge of block 23 which it is to engage. This pin, as seen more in detail in Fig. 9, is mounted in the longitudinal moving slide 21 90 and moves with it when the table top half 14 that is fast to that slide is pulled to the left, Fig. 1 or 4, to open the table. These pins 25 project far enough, one on each side of the table, as seen in Fig. 9, to engage the blocks 23, of which there is one at each side of the table, and to pull them along to the position illustrated in Fig. 5, thus setting up 95 their attached rail 22. The movement of the slides 21' caused by the pulling of the other half 14' of the table top produces a similar effect with the rail 22'; and this pair of rails thus are spread and elevated into positions such that the filling board 15, 15' can be set between them, as illustrated in Fig. 5. 100

Further movement of the slides 21, 21' is now prevented because the pins 25 therein are against the blocks 23 which are arrested by the blocks 24, and the first stage of extension is ready to be completed by the setting of the fillers. The doing of this automatically releases the pins 25 so that the slides can move further, for further extension. 105

The fillers 15, 15', 16, 16', 17, 17', are 115 flexible sheets, preferably made of strips of wood glued on cloth or other fabric 35 in the manner of the flexible covers customary in roll top desks. The strips 37 that are on the outside of the curve, are so placed that they 120 abut against each other and make a continuous smooth surface when the filler is drawn into a plane by entering the straight grooves. The backing pieces 36 are rounded to permit bending of the composite fabric, 125 and have their ends engaged either in guiding grooves 38 in the sides of the frame members 12^a or in the grooves 33, 33' in the rails 22, 22'. The communication is through the space left for that purpose in the mid- 130

dle between the two sections of plates 30^a, as seen in Fig. 7. The line on which this section is indicated in Figs. 4 and 5 cuts this filler but, for better showing, the filler is 5 represented as if uncut. The grooves 38 on one side of the table communicate with the grooves 30, 32 or 33 on the other side of the table. These grooves are recurved so that the half filler section, which on sliding into 10 its groove starts toward the opposite side of the table, curves around and heads toward its original side of the table and there comes to rest, overlapping the other half filler section which does likewise in the opposite direction. To draw forth the filler 15 sections little tabs 39 may be provided; and for holding securely together their ends, which come up last into the groove 33, a tongue 40 (Figs. 7 and 12) on one of them is 20 adapted to engage in a socket plate 41 at the adjacent end of the other, this connection being in the middle of the table top. As each of these sections stands up to the very middle, it interferes with the shifting of 25 the other section between the grooves 33 and 38; but this interference is easily avoided by backing one of them a short distance in its groove 30 and thus clearing the middle space so that the other can be shifted down 30 into its groove 38, after which the first one may be shifted into its groove 38. The act of setting the filling sections 15, 15' in the table top after the rails 22 have been shifted into the position shown in Fig. 5, causes 35 withdrawal of the pins 25 from their engagement with the blocks 23, which is shown in Fig. 5, by the means which is indicated very clearly in Fig. 9, wherein the small lever 26 is seen arranged in a suitable small slot in the sliding piece 21 and pivoted 40 at 27 so as at one end to engage the embedded part of the abutment pin 25 and at its other end to project up a little above the slide 21, far enough to be itself engaged by a lug 28 carried on one of the slats composing the 45 filler section 15'. When this filler section is drawn from the retired position of Fig. 7, to the set position of Fig. 8, the lug 28 encounters the lever 26 and pushes the up-standing end of this lever so that the other end of the lever pushes the abutment pin 25 into slide 21, against the spring 29, and holds it thus so long as the filler section 50 remains in place. The pin 25, being thus made free to move past the blocks 23 and 24, permits the further withdrawal of the slide 21 and table top 14 from the position of Fig. 5 to that of Fig. 6. This movement can proceed until the ultimate stop block 42 on the slide 21 engages the block 23. 55 The dimensions are so arranged that this occurs when the groove 30 of the edge of the table top is at a suitable distance from the groove 32 in the rail 22 to receive the filler sections 16 and 16' when pulled up out of 60 their storage grooves in the frame pieces 65 12 and 12^a corresponding to grooves 38 on the middle-facing side of the frame piece 12^a heretofore mentioned. These sections having thus been drawn up, and the sections 17 and 17' at the other end of the table having been drawn up similarly upon the withdrawal of the half 14' of the table top, the 70 complete extended top is made, as illustrated in Fig. 1. The extension can be stopped at either stage. The filler sections 75 are removed by reversing the process of extension. The section 16, for example, is first shifted a little in the direction which is upward in Fig. 1 in order to draw the tongue 40 out of the socket 41 and to open the path into 80 the groove 38; and then the section 16' is pushed down into said groove 38 followed by the pushing of section 16' down into the other part of the same groove. The filler sections 17 and 17' are similarly treated, and 85 sections 15 and 15'. The back of the pin 26 may be beveled so that the table top halves 14 and 14' can be returned to their inward limits, with each of these pins slipping by its block 24. As the slides 21 move inward, the 90 table top 14 engages the rail 22 while it remains held at the top level by block 24, particularly if this movement be executed before the central filler sections 15 and 15' are 95 put down. When those have been put down, 100 on further inward movement of the table top 14 the upper part of its edge pushes the rail 22 off of the block 24, and the lower part of said edge then pushes it the rest of the way to the position shown in Fig. 4. The similar parts at the other end of the table 105 are likewise moved toward the center; and when the two parts of the top come together, the rails 22 and 22' simultaneously come together. 110

The pin 25 is set at a little distance from the block 23 which it engages, so that on opening the top the part 14 travels from its position a distance equal to the width of the rail 22 before the pin engages the block 23 to begin the movement of that rail. Thus the part of the top which covers the rail 22 when in closed condition, Fig. 4, is out of the way so as not to obstruct the raising of the rail by the cam block 24. To accommodate the lever 26 for operating this pin, a suitable recess 45 is provided in the opposite half table top. 115

The operation of the table is very simple. It is only required to pull the top apart as far as it will go, and then to pull up central 120 filler sections 15, 15'. If it is desired to extend the table further, the top may then be pulled further open, having been automatically unlocked for this purpose by the pulling up of the central filler sections; and again it will stop at the proper place for the pulling up of either or both of the next filler sections. Upon closing, the table is left in neat and finished form, showing only 125 the customary crack in the middle of the 130

top. Obviously, the invention may be applied with the use of a different number of filler sections, and may be varied in other respects without departing from the scope 5 of the appended claims.

We claim as our invention:—

1. An extensible table having a top-frame combined with top-halves that slide apart thereon; filling boards adapted to intervene 10 between the top-halves; and movable rails adapted to intervene between the filling boards and the top-halves; there being grooves in said top-halves and in said rails adapted to receive and hold the filling 15 boards.
2. An extensible table having a top-frame combined with top-halves that slide apart thereon; filling boards; and depressible rails adapted to rise to the top level and to hold 20 the boards when raised, and to be covered by the top-halves when depressed.
3. An extensible table having a top-frame combined with top-halves that slide apart thereon; filling boards; and depressible rails adapted to rise to the top level and to hold 25 the boards when raised, and to be covered by the top-halves when depressed; there being means actuated by the top-halves for automatically raising said rails.
4. An extensible table having a top-frame combined with top-halves that slide apart thereon; filling boards; and depressible rails adapted to hold the boards when raised, and to be covered by the top-halves when 30 depressed; there being cams actuated by the top-halves for raising said rails.
5. An extensible table having a top-frame combined with top-halves that slide apart thereon; filling boards; and depressible rails adapted to hold the boards when raised, and to be covered by the top-halves when depressed; there being cams actuated by the top-halves for raising said rails, and stops 35 adapted to limit the rising movement of the rails to the level of the top-halves.
6. An extensible table having a top-frame combined with top-halves that slide apart thereon; filling boards; and rails adapted to hold them, said rails being separate from the top-halves, assembled at the middle of 40 the table top when the table is closed and being shiftable therefrom in the endwise direction of the table to their board-holding positions.
7. An extensible table having a top-frame combined with top-halves that slide apart thereon; filling boards; rails adapted to hold them, said rails being separate from the top-halves, assembled at the middle of 45 the table top when the table is closed; and means connected with the top-halves to pull the rails therefrom to their board-holding positions.
8. An extensible table having a top-frame combined with top-halves that slide apart 50

thereon; filling boards; rails adapted to hold them, said rails being assembled at the middle of the table top when the table is closed; and means connected with the top-halves to pull the rails therefrom to their 70 board-holding positions, comprising pins set in the sliding members, and depending blocks fixed to the rails and adapted to be engaged by said pins.

9. An extensible table having a top-frame 75 combined with top-halves that slide apart thereon; filling boards; and rails adapted to hold them, said rails being assembled at the middle of the table top when the table is closed and being shiftable therefrom in the 80 endwise direction of the table to their board-holding positions; blocks depending from the rails; and stops on the frame, adapted to limit movement of the blocks at the position where the rails register with the frame 85 for holding the filling boards.

10. An extensible table having a top-frame combined with top-halves that slide apart thereon; filling boards; rails adapted to hold them, said rails being assembled at 90 the middle of the table top when the table is closed; and means connected with the top-halves to pull the rails therefrom to their board-holding positions, comprising pins set in the sliding members, and depending 95 blocks fixed to the rails and adapted to be engaged by said pins; and members automatically releasing the engagement of pin with block, permitting the pin to pass the 100 block.

11. An extensible table having a top-frame combined with top-halves that slide apart thereon; filling boards; rails adapted to hold them, said rails being assembled at the middle of the table top when the table is closed; and means connected with the top-halves to pull the rails therefrom to their 105 board-holding positions, comprising pins set in the sliding members, and depending blocks fixed to the rails and adapted to be engaged by said pins; and means automatically actuated by the setting of the filling boards for releasing the engagement of pin with block and permitting the pin to pass the 110 block.

12. An extensible table having a top-frame combined with top-halves that slide apart thereon; filling boards; and rails adapted to hold them, said rails being assembled at the middle of the table top when 115 the table is closed and being shiftable therefrom in the endwise direction of the table to their board-holding positions; blocks depending from the rails; and stops on the frame, adapted to limit the movement of 120 the blocks at the position where the rails register with the frame for holding the filling boards; automatic releasing means for said stops, and further stops for the top-half in position where the top-half and the 125 130

outer edge of the previously stopped rail are properly spaced for receiving a filling board.

13. An extensible table having a top-frame combined with top-halves that slide apart thereon; filling boards; rails adapted to hold them, said rails being assembled at the middle of the table top when the table is closed; and means connected with the top-halves to pull the rails therefrom to their board-holding positions, comprising pins set in the sliding members, and depending blocks fixed to the rails and adapted to be engaged by said pins; and means automatically actuated by the setting of the filling boards for releasing the engagement of pin with block and permitting the pin to pass the block; the pin being spring-pressed outward and the said release being a lever arranged to be moved inward with the pin by the setting movement of a filling board.

14. An extensible table having a top-frame combined with top-halves that slide apart thereon; and filling boards and rails, which when the table is extended occupy positions in the top between said halves; the said rails and top-halves having grooves whereby they coöperate with each other and with the filling boards in forming an extended top.

15. An extensible table having a top-frame combined with top-halves that slide apart thereon; and filling boards and rails, which when the table is extended occupy positions on the top between said halves; the said rails and top-halves having grooves whereby they coöperate with each other and with the filling boards in forming an extended top; and means whereby said filling boards and rails are stored under the top-halves when the table is closed.

16. An extensible table having a top-frame combined with top-halves that slide apart thereon; filling boards; and rails for them intervening between the top-halves, the edges thereof having grooves to receive the filling boards; and there being also grooves for the filling boards in the frame under the top-halves; said grooves communicating in the middle for passage of the filling boards from one set of grooves to the other.

17. An extensible table having a top-frame combined with top-halves that slide apart thereon; filling boards; and rails for them intervening between the top-halves, the edges thereof having grooves to receive the filling boards; and there being also grooves for the filling boards in the frame under the top-halves; said grooves communicating in the middle for passage of the filling boards from one set of grooves to the other; and the grooves in the frame being below and separated from the level of the top but rising to its level in the middle.

18. An extensible table having a top-frame

combined with top-halves that slide apart 65 thereon, filling boards; and rails for them intervening between the top-halves, the edges thereof having grooves to receive the filling boards; and there being also grooves for the filling boards in the frame under the top- 70 halves; said grooves communicating in the middle for passage of the filling boards from one set of grooves to the other, the course of grooves in the frame extending by a curve 75 into reverse direction.

19. An extensible table having a top-frame combined with top-halves that slide apart thereon, filling boards; and rails for them intervening between the top-halves, the edges thereof having grooves to receive the filling 80 boards; and there being also grooves for the filling boards in the frame under the top-halves; said grooves communicating in the middle for passage of the filling boards from one set of grooves to the other, the course of 85 grooves in the frame extending by a curve into reverse direction with their ends overlying each other.

20. An extensible table having a top-frame combined with top-halves that slide apart 90 thereon; filling boards; and rails for them intervening between the top-halves, the edges thereof having grooves to receive the filling boards; and there being also grooves 95 for the filling boards in the frame under the top-halves; said grooves communicating in the middle for passage of the filling boards from one set of grooves to the other; the grooves in the rails being open at the edges 100 of the table whereby a filling board section can be backed out, away from the middle, to permit passage of its complementary section.

21. An extensible table having a top-frame combined with top-halves that slide apart thereon; filling boards; and rails for them 105 intervening between the top-halves, the edges thereof having grooves to receive the filling boards; and there being also grooves for the filling boards in the frame under the top-halves; said grooves communicating in 110 the middle for passage of the filling boards from one set of grooves to the other; said grooves in the rails and top-halves being formed as a rabbet in the corner and made with addition of a metal strip to form the 115 third side thereof.

22. An extensible table having a top-frame combined with top-halves that slide apart thereon; filling boards; and rails for them intervening between the top-halves, the 120 edges thereof having grooves to receive the filling boards; and there being also grooves for the filling boards in the frame under the top-halves; said grooves communicating in the middle for passage of the filling boards 125 from one set of grooves to the other; said filling boards being each in two sections, one for each side of the table, adapted to be

moved thence downward through the middle into the frame grooves.

23. An extensible table having a top-frame combined with top-halves that slide apart thereon; filling boards; and rails for them intervening between the top-halves, the edges thereof having grooves to receive the filling boards; and there being also grooves for the filling boards in the frame under the top-halves; said grooves communicating in the middle for passage of the filling boards from one set of grooves to the other; said filling boards being each in two sections, one for each side of the table, adapted to be moved thence downward through the middle into the frame grooves, and means whereby the two sections interlock when abutting together in the top.

24. An extensible table having a top-frame combined with top-halves that slide apart thereon; filling boards; rails for holding them, depressible from the top level and shiftable in the direction of the length of the table; and means on the frame to support said rails when raised.

25. An extensible table having a top-frame combined with top-halves that slide apart thereon; filling boards; rails for holding them, depressible from the top level and shiftable in the direction of the length of the table; and means, comprising a support on the frame, to raise said rails.

26. An extensible table having a top-frame combined with top-halves that slide apart thereon; flexible filling boards; and movable rails for holding them; the rails moving lengthwise of the table and the filling boards

crosswise of the table, in shifting between positions of storage and of use.

27. An extensible table having a top-frame combined with top-halves that slide apart thereon, and filling boards arranged in storage in said frame in a plurality of positions along the longitudinal travel; there being a movable formation of the top adapted to receive them and means whereby said formation can be set and automatically stopped in positions registering successively with said storage positions before the said board in the particular position is removed therefrom.

28. An extensible table having a top-frame combined with top-halves that slide apart thereon; filling boards; and rails adapted to hold them in the top, said rails being depressible to storage positions; there being recesses rabbeted in the adjacent edges of said top-halves for housing said rails when depressed.

29. An extensible table having a top-frame combined with top-halves that slide apart thereon; filling boards; and rails adapted to hold them, said rails being assembled between the top-halves and within the planes formed by the upper and lower sides of the top-halves when the table is closed and being shiftable therefrom in the endwise direction of the table to their board-holding positions.

Signed at Boston, Massachusetts, this fif- 70
teenth day of March, 1919.

HARRY WINBERG.
CHARLES WINBERG.
